THERMOSTAT

Filed April 14, 1931

UNITED STATES PATENT OFFICE

ALONZO A. WARNER, OF NEW BRITAIN, CONNECTICUT, ASSIGNOR TO LANDERS, FRARY & CLARK, OF NEW BRITAIN, CONNECTICUT, A CORPORATION OF CONNECTICUT

THERMOSTAT

Application filed April 14, 1931. Serial No. 529,943.

The present invention relates to thermostats and especially to a temperature control switch having a positive snap action to "on" and "off" positions.

5 The principal object of the invention is to provide a temperature control switch having a movable contactor under the control of a spring constantly urging it to the "on" position and, under certain temperature conditions, maintaining the movable contactor in "off" position.

Other objects and advantages of the invention will appear from the following description taken in connection with the accompanying drawing which illustrates, by way of example, a preferred embodiment of the invention and in which—

Figure 1 is a fragmentary side elevation, partly broken away, illustrating a preferred 20 form of the invention;

Figure 2 is a vertical longitudinal sectional view through the thermostat of Fig. 1, on a slightly enlarged scale, taken on the line 2—2 of Fig. 4;

25 Figure 3 is a similar sectional view taken on the line 3—3 of Fig. 4;

Figure 4 is a bottom plan view;

Figure 5 is a vertical transverse section taken on the line 5—5 of Fig. 2;

30 Figure 6 is a horizontal sectional view taken on the line 6—6 of Fig. 5; and

Figure 7 is a vertical transverse sectional view on the line 7—7 of Fig. 2.

Referring in detail to the drawing, the 35 thermostat includes a base plate 12 having at one end a raised seat 14 provided with a threaded opening for the reception of a screw 16 which holds in place upon the seat a bi-metallic temperature-responsive leaf spring 18 normally having the form of Fig. 2 but, under predetermined increase of temperature, assuming the shape illustrated in Fig. 3.

40 At the end of the base plate opposite to the seat 14 there is located an angle plate 22 whose horizontal portion is secured to the base plate by rivets 24, or otherwise. To the inner face of the angle plate is secured, by rivets 26 or otherwise, an insulator strip 28 45 in which are mounted a pair of terminals 30,

32, each in contact with a fixed contactor strip 34 extending vertically, as shown in Figs. 3 and 7.

Fixed on the horizontal arm of the angle plate 22 is a bracket 36 having vertically extending parallel arms 38 provided with aligned openings 40 for the reception of the oppositely extending spindles 42 of a movable contactor 44 provided with an insulated conductor 46 adapted to bridge the fixed contactor strips 34, as in the position of Figs. 2 and 6, for closing the circuit, and to occupy the position of Fig. 3 upon opening of the circuit. The arms 38 of the bracket are preferably provided with inwardly extending substantially horizontal rests 48 to support the weight of the rocking contactor 44, as illustrated in Figs. 2 and 3.

The invention provides an actuator for movable contactor 44 and, in the present embodiment of the invention, this actuator has the form of a right angular rocking plate 50 bent at right angles to form a heel 52, the bent portion serving to carry a revolubly mounted roller 54 adapted to be contacted, 75 as illustrated in Fig. 3, by the bi-metallic leaf spring 18 upon increase of temperature. The base 12 is provided with a struck-up tongue or flange 56 which limits bodily movement of the roller 54, and consequently of the actuator 50, in one direction. The actuator is provided near its heel 52 with one or more slots or openings through which extend a corresponding number of projections 58 formed on the bottom of the bracket 36, bodily movement of the actuator 50 being thereby limited toward the right, as viewed in Figs. 2 and 3, the extensions 58 also cooperating with the flange 56 to maintain the actuator, at all times, in assembled operative position. 80

The invention provides a resilient connection between the actuator and the movable contactor, in this instance having the form of a U-shaped spring clip 60, whose bent ends tend constantly to move toward each other, one of the ends being hooked into the movable contactor 44 (see Figs. 3 and 5) and the other end being in engagement with the actuator. When in assembled position, the ends of the spring clip are held apart from each other 100

under tension by the two members to which the clip is attached.

In operation, assuming the parts to be in the position of Fig. 2 with current flowing through the heating resistance in housing 64, with a socket over a pair of pin contacts, one for conductor 66 and one for conductor 68, the current will flow through the conductor 68 into one of the fixed contact strips 34, across the bridge of the movable contactor 44, thence through the other contact strip 34, then through the conductor 70, the resistance, and conductor 66. When, due to the heating resistance the temperature of the bi-metallic leaf spring increases sufficiently and it bears upon the roller 54, as illustrated in Fig. 3, the roller will be urged toward the base 12, and, due to the spring 60, the actuator will rock on its heel 52 with a snap action from the position of Fig. 2 to the position of Fig. 3. In case the contacts 46 and 34 stick or weld together, a finger 74 on the actuator will bear against a projection 76 on the movable contactor and force the contactors 46 and 34 apart, so that spring 60 can effect the snap rocking movement of the movable contactor about its axis. It will be observed that at the start of this movement, both engaged ends of the spring clip 60 are on the same side of a vertical plane containing the rocking axis of the movable contactor. As the movable contactor is forced to the position of Fig. 3, it will be evident from the drawing that the ends of the spring are forced further apart until both ends of the spring clip lie on the other side of said vertical plane. The moment these ends pass through said plane the tension of the spring clip causes its ends to draw nearer together and hold the parts in the position of Fig. 3, in which the bridging contact 46 has opened the heating circuit. The parts are so proportioned and arranged that finger 74 will not engage projection 76 on the movable contactor when the parts are working freely, the spring 60 normally functioning in time to prevent this engagement. With the construction described, there is provided a spring-governed snap action in opening the circuit. With the heating resistance out of circuit and the bi-metallic leaf spring 18 cooling, its free end will move away from the roller gradually and the parts will begin to move gradually to the position of Fig. 2. Although the movement of the actuator 50 may be very gradual, the moment the engaged portions of the spring clip pass through the vertical plane of the movable contact axis, the arms of the spring clip move toward each other under their own tension and snap the movable contactor to the position of Fig. 2, or closed circuit position, thus again bringing the heating resistance into action.

The invention provides means for varying the time of the operating intervals of the

thermostat, and for this purpose, in the form shown, fingers 78 are provided on the actuator 50. The time intervals may be shortened by bending one or both of these fingers in the direction of the contactor 44.

It will be evident that washers may be placed between the leaf spring and its seat in order to vary the distance between the free end of the spring and the roller 54, thereby varying the temperature at which the circuit is opened or closed. It will also be apparent that since the ends of the spring clip are always on the same side of a vertical plane, including the line of the heel 52, the effect of the spring clip is always to tend to move the actuator to the position of Fig. 2.

What is claimed is:

1. A thermostat including a pair of stationary contacts, a yieldable operating element, an actuator movable thereby to open and closed circuit positions, a movable contactor, and a spring cooperating with said actuator and said contactor, said spring constantly urging said actuator toward circuit closing position and also urging said contactor toward said contacts in closed circuit position of said actuator and away from said contacts in open circuit position of said actuator.

2. A thermostat including a pair of stationary contacts, a temperature responsive element, a rocking actuator movable thereby to open and closed circuit positions, a movable contactor, and a spring cooperating with said actuator and said contactor, said spring constantly urging said actuator toward circuit closing position and also urging said contactor toward said contacts in closed circuit position of said actuator and away from said contacts in open circuit position of said actuator.

3. A thermostat including a pair of stationary contacts, a temperature responsive element, an actuator movable thereby, a movable contactor, and a spring clip having a pair of arms constantly urged toward each other, one engaging said actuator and the other said contactor, said spring constantly urging said actuator toward circuit closing position and also urging said contactor toward said contacts in closed circuit position of said actuator and away from said contacts in open circuit position of said actuator.

4. A thermostat including a pair of stationary contacts, a temperature responsive element, an actuator rockable thereby about an axis, a contactor rockable about a substantially parallel axis, and a spring clip having a pair of arms one engaging said contactor between said axes and the other engaging said actuator.

5. A thermostat including a pair of stationary contacts, a temperature responsive element, an actuator rockable thereby about an axis, a contactor rockable about a substan-

- tionally parallel axis, and a spring clip having a pair of arms one engaging said contactor between said axes on one side of said contactor axis and the other engaging said actuator on 5 the other side of said contactor axis.
6. A thermostat including a pair of stationary contacts, a temperature responsive element, an actuator rockable thereby about an axis, a contactor rockable about a substantially parallel axis and having a portion between said axes engageable by said actuator, and a spring clip having a pair of arms one engaging said contactor between said axes and the other engaging said actuator.
- 10 7. A thermostat including a pair of stationary contacts, a temperature responsive element, an actuator rockable thereby about an axis, a bracket having substantially parallel arms, a contactor pivotally mounted there- 20 in to rock about a substantially parallel axis, and a spring clip having a pair of arms one engaging said contactor between said axes and the other engaging said actuator.
8. A thermostat including a pair of stationary contacts, a temperature responsive element, an actuator rockable thereby about an axis, a bracket having a pair of substantially parallel arms provided with contactor rests, a contactor carried by said rests and 30 pivoted loosely in said arms to rock about a substantially parallel axis, and a spring clip having a pair of arms one engaging said contactor between said axes and the other engaging said actuator.
- 35 9. A thermostat including a pair of stationary contacts, a temperature responsive element, an actuator movable thereby to open and closed circuit positions, a movable contactor, and a spring cooperating with said 40 actuator and said contactor, said spring constantly urging said actuator toward circuit closing position and also urging said contactor toward said contacts in closed circuit position of said actuator and away from said 45 contacts in open circuit position of said actuator, said actuator having a portion engageable with said movable contactor during movement of said actuator to open circuit position at substantially the moment when the 50 direction in which said spring urges said movable contactor is about to change.
10. A thermostat including a pair of stationary contacts, a yieldable operating element, an actuator movable thereby to open 55 and closed circuit positions, a movable contactor, a spring cooperating with said actuator and said contactor, said spring constantly urging said actuator toward circuit closing position and also urging said contactor 60 toward said contacts in closed circuit position of said actuator and away from said contacts in open circuit position of said actuator, and means for varying the operating intervals of said thermostat.
- 65 11. A thermostat including a pair of sta-
- tionary contacts, a yieldable operating element, an actuator movable thereby to open and closed circuit positions, a movable contactor, a spring cooperating with said actuator and said contactor, said spring constantly urging said actuator toward circuit closing position and also urging said contactor toward said contacts in closed circuit position of said actuator and away from said contacts in open circuit position of said actuator, and bendable fingers on said actuator for varying the operating intervals of said thermostat.
